The ornamental design for a cushion to be placed on a ramp to slow down a wheel chair, as shown and described.

DESCRIPTION

FIG. 1 is a top and end perspective view of a cushion to be placed on a ramp to slow down a wheel chair showing my new design;

FIG. 2 is a side elevational view thereof, the opposite side being a mirror image of that shown;

FIG. 3 is an enlarged end elevational view thereof, the opposite end being a mirror image of that shown;

FIG. 4 is a top plan view thereof; and,

FIG. 5 is a reduced bottom and end perspective view thereof.

FIG. 2

FIG. 3

FIG. 4
